UNITED STATES PATENT OFFICE.

CHARLES T. ROSENTHAL, OF BATESVILLE, ARKANSAS.

TEMPORARY BINDER.

SPECIFICATION forming part of Letters Patent No. 619,228, dated February 7, 1899.

Application filed July 16, 1898. Serial No. 686,144. (No model.)

To all whom it may concern:

Be it known that I, CHARLES T. ROSENTHAL, of Batesville, in the county of Independence and State of Arkansas, have invented a new and Improved Temporary Binder, of which the following is a full, clear, and exact description.

The object of my invention is to provide a temporary binder that may be constructed in sections, each section being capable of independent use, and each section being furthermore so constructed that the leaves contained in a section may be removed without disturbing those of an adjoining section.

15 A further object of the invention is to provide a means whereby the sections may be locked closed and readily opened when necessary.

The invention consists in the novel construction and combination of the several parts, as will be hereinafter fully set forth, and pointed out in the claims.

Reference is to be had to the accompanying drawings, forming a part of this specification, 25 in which similar characters of reference indicate corresponding parts in all the views.

Figure 1 is a perspective view of a book bound by the improved temporary binder, the upper cover being open and broken away.

30 Fig. 2 is an edge view of the book shown in Fig. 1 with both covers closed. Fig. 3 is a view of the back of a bound book, the cover for the binding device having been removed.

Fig. 4 is a section taken substantially on 35 the line 4-4 of Fig. 3, the covering for the binding device being applied. Fig. 5 is a perspective view of one end of one member of a section of a temporary binder. Fig. 6 is a perspective view of a section of the temporary

40 binder closed, being viewed from the rear. Fig. 7 is a perspective view of the section of the temporary binder shown in Fig. 6 viewed from the front. Fig. 8 is a perspective view of a section of the temporary binder, the section being in open position. Fig. 9 is a perspective view of a lower member of a section of the temporary binder. Fig. 10 is perspective view of the locking bar or plate employed in connection with a section of the temporary 45 binder. Fig. 11 is a perspective view of a section of the temporary binder viewed from the rear, a part of the back of the section be-

ing broken away. Fig. 12 is a perspective view of a spring-guide for the locking guard or plate of a section of the binder. Fig. 13 55 is a transverse section taken through a section of the temporary binder, the section of the binder being closed; and Fig. 14 is a view similar to Fig. 13, the section of the binder being open and the section from the binder 60 in Fig. 14 is taken practically on the line 14-14 of Fig. 8.

A represents a section of the improved temporary binder, which section comprises a top plate *a* and a bottom plate *a'*, the two plates 65 having a hinged connection. The top plate *a* is provided at its back or rear edge with a downwardly-extending flange, upon which flange knuckles 10 are produced at intervals, and the said flange at the back of the top plate 70 *a* is cut away at the center to form a longitudinal opening 11. Pins 12 are secured to the top plate *a*, and the said pins extend downward or from the inner face of the said top plate in direction of the bottom plate *a'*. Between 75 the center and each end of the top plate *a* of the binder a stationary guide 14 is located. Each of the said guides 14, as shown best in Figs. 11, 13, and 14, consists of a plate riveted or otherwise secured to the under face 80 of the top plate or member *a*, extending therefrom in direction of the lower plate or member *a'*, the lower end of the guide-plate 14 being rearwardly curved and then carried upwardly and forwardly, preferably on a curved 85 line, to form a hook-section 14^a. The bottom plate or member *a'* of a section of the binder is provided with an upwardly-extending flange at its back or rear edge, formed with knuckles 15, adapted to enter the spaces between the knuckles 10 in the upper plate or member *a*, and the hinged connection between the two members or plates is effected by passing a pin or pintle 10^a through the knuckles of the two members of the section. 90 95

The lower member or plate *a'* of a section of the binder is provided with upwardly-extending pins 16, and these pins are adapted to pass between or alternate with the pins 12 of the upper member *a*. The lower member 100 or plate *a'* is provided with an opening at the central portion of its back corresponding to the opening 11 in the top member, (designated as 11^a), and the bottom member is

also provided with fixed guide-plates 17, that correspond to the guide-plates 14 of the upper member; but the guide-plates on the lower member *a'* extend upwardly and are so placed 5 as to alternate with those of the upper member. The hook-sections 17^a of the fixed guide-plates 17 extend downwardly instead of upwardly, as do the corresponding portions of the guide-plates of the upper member of a section. 10 I desire it, however, to be understood that the hook-sections of the fixed guide-plates need not necessarily extend the length of the body of said guide-plates, as shown best in Figs. 9 and 11.

15 In connection with each section of the binder a locking plate or bar 18 is employed. This locking plate or bar is transversely curved, and when the two members of a section are closed the locking plate or bar is 20 passed between the body portions of the fixed guide-plates 14 and 17 and their hook portions 14^a and 17^a, as is shown particularly in Figs. 8 and 11. The locking plate or bar 18 is provided with recesses 19 in its upper edge and 25 with recesses 20 in its lower edge, the recesses in the upper edge corresponding to the number of fixed guide-plates on the upper member of the binder-section, and the recesses in the bottom of the said locking plate or bar are 30 so located that when the said locking plate or bar is drawn outward to a certain extent the said recesses will be opposite the hook portions of the said guide-plates and will permit the upper member of the binder-section to be 35 opened or carried at an angle to the lower member, as shown in Fig. 8. When, however, the solid portions of the locking plate or bar are carried between the hook and body portions of the fixed guide-plates, the members of the section of the binder will be locked 40 in a closed position and cannot be opened, as shown in Fig. 11. This latter position of the locking plate or bar is maintained by means of a spring-controlled guide B. (Shown 45 applied in Figs. 3, 6, 8, and 11 and in detail in Fig. 12.) This spring-guide B consists of a knuckle 23, through which the pintle 10^a of the hinge for the members of the section passes, and oppositely-extending ears 50 24, near the ends of the said knuckle, which ears are adapted to engage with the inner faces of the back flanges of the members of the binder-section, and between the ears 24 a two-part projection 25 is formed upon the 55 knuckle 23, which double-leaved projection is adapted to enter a slot 21 in the locking bar or plate 18 and then have its leaves turned in opposite directions, as shown in Fig. 8. A spring 26 is coiled around the pintle, on which 60 the guide B is mounted, and the spring serves to hold the guide in a position that will compel the locking plate or bar to lock the members of the binder-section closed. When it is desired to open the binder-section for the 65 purpose of introducing leaves or of removing leaves therefrom, the locking-plate is drawn outward, as shown in dotted lines in Fig. 7

and in positive lines in Fig. 8, thus placing the spring 26 of the section under tension.

A lug 28 is located at one end of either the 70 upper or the lower member of the binder-section, the said lug being so placed as to form a guide or gage for inserting loose leaves. In Figs. 1, 2, 3, and 4 I have illustrated a number of sections combined together, and the 75 backs of the sections are covered by a suitable strip 29. When the sections are combined, the fixed guide-plates 14 for the upper members of the sections are secured to the under face of the bottom member of the next 80 section above. When a cover 30 is to be employed, the upper member of the upper section and the lower member of the lower section are provided with knuckles 31, between which knuckles 32 are placed, said knuckles 85 32 being secured to the cover, a pintle passing through the alining knuckles. The leaves are provided with apertures 33, through which the pins of the members of a binder-section 90 are passed.

Having thus described my invention, I claim as new and desire to secure by Letters Patent—

1. In a binder for leaves or for similar purposes, an upper and a lower member having 95 a hinged connection, said members being provided with means for holding leaves between them, guide-plates secured to the inner faces of said members, the guide-plates for the two members extending in opposite directions and being placed out of vertical alinement, each guide consisting of a body and a hook-section carried by the body, and a locking-plate held to slide between the hook and the body-sections of the guides, said locking-plate being 100 provided with recesses arranged to register with the hook portions of the said guides, as and for the purpose set forth.

2. In a binder for leaves or other purposes, 105 an upper and a lower member having a hinged connection and means for holding leaves between them, guide-plates secured to the inner faces of the two members, the guide-plates for the members being alternately arranged, each guide-plate comprising a body and a return-section from the body, and a spring-controlled locking-plate fitted to slide between the bodies of the guide-plates and their return portions, the said locking-plate being provided with recesses capable of simultaneously 110 registering with the return portions of all of the guide-plates, for the purpose set forth.

3. In a temporary binder or a binding device, the combination, with an upper and a lower member having a hinged connection, 115 and guides fixedly secured to the inner faces of the two members, the guides of the members being arranged to alternate, each guide consisting of a body and a return portion, of a tension-controlled locking plate or bar 120 mounted to slide between the body and return portions of said guides, the said locking plate or bar being provided with recesses in its upper and in its lower edges, which recesses are 125 130

adapted in one position of the said locking plate or bar to receive the return portions of the said guides, for the purpose set forth.

4. In a temporary binder, the combination of two hinged members, guide-plates respectively secured to said members, and a locking-plate slidably mounted on the guide-plates and adapted to coact with them, whereby to lock or release the hinge of said members.
5. In a temporary binder, the combination of two hinged members, guide-plates respectively secured to said members and having each an inturned end or hook portion, and a locking-plate having sliding connection with 15 said inturned ends or hook portions, the lock-

ing-plate being formed with notches capable of registering with the hook portions.

6. In a temporary binder, the combination of two hingedly-connected members, a locking-plate carried by the binder and having 20 notches in its edges, and means carried by each of said members for engaging the locking-plate, whereby to hold the members immovable, the locking-plate being slidable to place means and the notches in juxtaposition 25 to permit the movement of the members.

CHARLES T. ROSENTHAL.
